UNITED STATES PATENT OFFICE.

EDGAR BENJAMIN KERST, OF PHILADELPHIA, PENNSYLVANIA.

SECTION-LINER.

938,769.

Specification of Letters Patent.

Patented Nov. 2, 1909.

Application filed March 8, 1909. Serial No. 481,975.

To all whom it may concern:

Be it known that I, EDGAR BENJAMIN KERST, a citizen of the United States, residing at Philadelphia, in the county of Philadelphia and State of Pennsylvania, have invented certain new and useful Improvements in Section-Liners, of which the following is a specification.

My invention relates to an improved section liner, and more particularly adapted for use in connection with a drafting machine, such as known to the trade as the Universal drafting machine, but is in no wise limited to this particular machine.

The object of the invention is to provide improved step by step operating means for the straight edge, whereby the latter will be moved a uniform distance with each operation, so as to exactly position the section lines relative to each other.

A further object is to provide improved means of this character, which are capable of wide adjustment, so as to move the straight edge the desired distance at each operation for section lining.

With these and other objects in view, the invention consists in certain novel features of construction, and combinations and arrangements of parts as will be more fully hereinafter described and pointed out in the claims.

In the accompanying drawings, Figure 1, is a broken plan view illustrating the application of my improvements. Fig. 2, is a view in section on the line 2—2 of Fig. 1 through a drawing board showing my improvements in elevation. Fig. 3, is an enlarged plan view of the device. Fig. 4, is a view in longitudinal section on the line 4—4 of Fig. 3, and Figs. 5 and 6 are views in cross section on the lines 5—5 and 6—6 respectively of Fig. 3.

1 represents a drawing board, and 2 a horizontal straight edge of an ordinary drafting machine as illustrated at 3.

My improved device comprises a rod 4 supported at its ends in sheet metal brackets 5, which latter are clamped around the rods by clamping bolts 6. The brackets are each made with outwardly projecting feet 7, having screw threaded pins 8 adjustable in said feet, and made with sharpened inner ends so as to be projected into the drawing board and support my improvements in place.

9 represents a sheet metal frame, which is

positioned across and secured to the straight edge 2 by means of screws 10. This frame is provided with upturned ends 11, having openings 12 to receive the rod 4, and slide 60 freely thereon. The frame is also made with an upturned perforated ear 13 to receive a screw threaded adjusting rod 14, mounted in an opening in one upturned end 11, and projecting through the opening in ear 13, and 65 is provided with a milled head 15 on one end and nut 16 on its other end, so as to securely hold the rod in place.

A sleeve 17 is mounted to slide upon the rod 14, and is fixed to a lever 18, the latter 70 having an opening 19 mounted upon rod 4, and a milled adjusting nut 20 is located on rod 14 between the lever 18 and the ear 13, so as to assist in the adjustment of parts as will more fully hereinafter appear. A bent 75 lever 21 is also provided with an opening 22 to receive rod 4, and has a bifurcated lower end 23 straddling rod 14. A coiled spring 24 surrounds rod 4 between levers 18 and 21, and exerts pressure on the lever 21, so as 80 to compel the same to clamp upon the rod and hold the frame against accidental movement.

The operation of this portion of my improvements is as follows: When the operator grasps levers 21 and 18 and forces them toward each other, the lever 18 will move toward lever 21, the latter clamping on the rod 4. This movement is limited by the end of sleeve 17 engaging lever 21, and when 90 the levers are released, lever 18 will hold, while lever 21 and the frame 9 carrying the straight edge 2, will be forced to the left by means of the spring 24, until the head 15 engages the upturned end 11 of frame 9. It will 95 thus be seen that the length of movement at each operation can be regulated by adjusting the sleeve 17 on rod 14, and by positioning the nut 20.

To prevent any accidental retrograde 100 movement of the frame, I have provided a clamping lever 25, having its lower end contracted and positioned within an opening 26 in frame 9. This lever 25 is provided with an opening 27 adapted to clamp around rod 105 4, and a spring 28 located between an upturned end 11 and the lever 25 exerts pressure on the latter, so as to compel it to clamp the rod and prevent accidental movement of the frame. When it is desired to return the 110 frame to its former position, it is necessary to grasp this lever and press it toward the

end of the frame and hold it, while the frame is being moved backward.

A great many slight changes might be made in the general form and arrangement 5 of parts described without departing from my invention, and hence I do not restrict myself to the precise details set forth, but consider myself at liberty to make such changes and alterations as fairly fall within 10 the spirit and scope of the claims.

Having thus described my invention what I claim as new and desire to secure by Letters Patent is:

1. In a device of the character described, 15 the combination with a supporting rod, a frame mounted to move upon said rod, clamping levers connected with said frame and mounted on the rod, a spring between said clamping levers, a screw threaded rod 20 supported in the frame, a sleeve on one of said clamping levers adapted to engage the other and limit the movement of said levers toward each other, and means for adjusting said sleeve on said rod.
- 25 2. In a device of the character described, the combination with a supporting rod, a frame mounted to move upon said rod, clamping levers connected with said frame and mounted on the rod, a spring between 30 said clamping levers, a screw threaded rod supported in the frame, a sleeve on one of

said clamping levers adapted to engage the other and limit the movement of said levers toward each other, said sleeves having internal screw threads to mesh with the screw 35 threads on said threaded rod, a milled head on said screw threaded rod, and a milled adjusting nut on said rod back of the sleeve, whereby said sleeve may be adjusted and its length of movement limited.

3. In a device of the character described, the combination with a supporting rod, of a frame mounted to move upon said rod, clamping levers connected with said frame and mounted on the rod, a spring between 45 said clamping levers, an adjusting rod supported in the frame, a sleeve fixed on one of said clamping levers adjustable on the rod, and adapted to limit the movement of said clamping levers toward each other, a 50 milled head on said adjusting rod, and a milled adjusting nut on said rod back of the sleeve, whereby said sleeve may be adjusted on the rod to adjust the length of the movement of the frame.

In testimony whereof I have signed my name to this specification in the presence of two subscribing witnesses.

EDGAR BENJAMIN KERST.
